UNITED STATES PATENT OFFICE.

FRED L. BAILEY, OF ST. LOUIS, MISSOURI.

WINDOW-SHADE ADJUSTER.

SPECIFICATION forming part of Letters Patent No. 606,263, dated June 28, 1898.

Application filed June 21, 1897. Serial No. 641,723. (No model.)

To all whom it may concern:

Be it known that I, FRED L. BAILEY, a citizen of the United States, residing in the city of St. Louis, State of Missouri, have invented 5 a new and useful Improvement in Window-Shade Adjusters, of which the following is a full, clear, and exact description, reference being had to the accompanying drawings, which are made a part of this specification.

10 My invention relates to improvements in the mechanism for lowering or raising the roller which ordinarily carries the window-shade; and it consists of features of novelty, which will be more fully and perfectly pointed 15 out in the following description, in which—

Figure 1 shows the window-casing and the shade-adjuster in place with window-shade attached, part of the shade being broken away to more fully show the mechanism of the adjuster. Fig. 2 shows a detail view of one end of the adjuster-frame. Fig. 3 shows an end view of the detail in Fig. 2. Fig. 4 shows a detail guide-rail, the use of which will be subsequently pointed out. Fig. 5 is a detail 25 cross-section on line 5 5 of Fig. 2. Fig. 6 shows a modification of the adjuster-frame. Fig. 7 is a horizontal cross-section on line 7 7 of Fig. 6. Fig. 8 shows a second modification of the adjuster-frame. Fig. 9 is a cross-section on line 9 9 of Fig. 8. Fig. 10 shows an alternative form for attaching the lower roller of the adjuster-frame.

The window-casing 1 has secured on either side a vertical guide-rail 2. This guide-rail 35 is made of metal in the form of a small angle-bar, as is clearly shown in cross-section, Fig. 5. A top view of rail 2 is shown in Fig. 4. These guide-rails 2 extend from the top of the inside of the window-casing to the window-sill at the bottom. Between these rails is arranged a rigid carrier supporting at its 40 upper end the shade-roll. This carrier, which will be called the "adjuster," consists of a triangular frame 3, having small grooved rollers 4 at the upper and lower corners. These rollers 4 engage the guide-rail 2, and the two frames 3 are separated and held rigidly apart by a rod 5. This rod 5 passes through a collar 6 on each of the triangular 45 adjuster-frames and is held secure by a small set-screw or other means of clamping. The sleeve 6 is made so that the rod 5 can pass

through it, in this way adjusting the width between the rollers 4 on the two sides of the window. A small angle-bracket 7 is secured 55 to the upper part of each of the adjuster-frames and extends out, as shown in Fig. 3, clear over the frame 3. These brackets support the shade-roller 8, on which the curtain 9 is rolled. These brackets 7 are made with 60 a longitudinal slot 10 in their base, so that they may be adjusted to the exact length of the shade-roller 8. The entire adjuster-frame is held in its relative vertical position by the spring-catches 11, which engage small recess- 65 holes 12 in the guide-rail 2. These spring-catches 11 are released by the cord 13, which passes through an opening in the rod 5 and over a small pulley 14 at the top of the window-casing. 70

The operation of this adjuster is as follows: Presuming the window-shade to be in the position indicated in Fig. 1, first it is desired to raise the window-shade to the top of the window. The cord 13 is grasped and gently 75 pulled. It first releases the catches 11 from the holes 12 in the guide-rail 2. Next, further tension put on cord 13 raises the adjuster-frame vertically. The rollers 4 travel in the guide-rails 2. When the window-shade is 80 high enough, the cord 13 is released. The adjuster-frame will then descend until the catches 11 meet the first of the holes 12, into which they will enter, thereby arresting the downward course of the adjuster-frame. Of 85 course if the catches 11 happen to be opposite any of the holes 12 when the cord 13 is released they will at once enter such holes 12. If it is desired to lower the top of the window-shade, the cord 13 is first tightened enough to 90 release the catches 11. Then cord 13 is gently released, allowing the adjuster and window-shade to descend. The weight of the adjuster-frame and window-shade being much greater than the strength of the small springs 95 which force the catches 11 into their respective openings 12, the catches will remain disengaged so long as there is even a slight tension on cord 13; but so quick as cord 13 is entirely released the catches 11 will at once 100 engage in the nearest opening 12.

When the window frames or casings are not of sufficient depth to place angle-rails, as shown in Figs. 4 and 5, inside the casing,

then in order to make this invention available in such cases a small raised rail 15, such as is shown in Fig. 7, may be secured to the front of the window-easing 1. In this case either the form of adjuster-frame shown in detail Fig. 2 may be used or the rails may be placed so that the small grooved rollers 4 embrace the rail from the outside rather than press against them from the inside, as is clearly shown in Fig. 6. In this way the window-shade when pulled down will obscure the rail 15 from view within the room. On Fig. 6 will also be found a modified form of catch 11, operating by gravity instead of by spring. In the rail 15 (shown in Fig. 6) will be found a modified form of orifice for the catch 11 to engage with, consisting of a small triangular notch 16. Where it is desired to plan the window-case 1 originally for the use of this form of window-shade adjuster, a grooved rail 17, such as is shown in Fig. 9, may be mortised into the inside of the casing. In this groove the small rollers 4, which in this case need not be grooved, will travel. The weight of the adjuster-frame, and window-shade may be counterbalanced by weight 18, moving on the inside of the casing 1 in a manner similar to the counterweights for an ordinary window. Instead of catch 11 being used friction-springs 19 are intended to press against the bottom of the grooved rail 17, forming sufficient resistance to maintain the frame in any desired position, which can be done by a cord secured to the cross-bar 5,

passing over a pulley 14, similar to the cord 35 13, and also a cord attached to 5 and hanging directly down. (Not shown.)

Fig. 10 shows a modified form of securing the lower of the small rollers 4 by a spring 20, the object of this being to allow for slight 40 unevenness in the rail 2.

Having fully described my invention, the combination I claim is as follows:

1. In a window-shade adjuster, the combination of a rod having brackets at either end, 45 the same being laterally adjustable, rollers mounted at the upper and lower extremities of the brackets, guide-rails secured to the window-frame for engaging the rollers and a catch for holding the frame at any desired 50 position, and shade-roller brackets mounted upon a frame for holding the shade-roller substantially as described.

2. The combination in a window-shade adjuster of a rod 5, brackets 3; means for adjusting the brackets 3 laterally on the rod 5, rollers 4 mounted at the upper and lower extremities of the brackets 3, guide-rails 2 secured to the window-frame, brackets 7 for holding the shade-roller, the roller 8 for holding the shade and the catches 11 for securing the frame at any desired position, substantially as described.

FRED L. BAILEY.
